Attorney

Patented Sept. 30, 1924.

UNITED STATES PATENT OFFICE.

STANLEY F. NASH, OF KINGSTON, PENNSYLVANIA.

LINE CHALKER.

Application filed March 27, 1923. Serial No. 628,154.

To all whom it may concern:

Be it known that I, STANLEY F. NASH, a citizen of the United States, residing at Kingston, in the county of Luzerne, State of Pennsylvania, have invented certain new and useful Improvements in Line Chalkers; and I do hereby declare the following to be a full, clear, and exact description of the invention, such as will enable others skilled in the art to which it appertains to make and use the same.

This invention relates to new and useful improvements in marking devices, and particularly to chalk lines.

15 The principal object of the invention is to provide a device for applying chalk to the line and which is simple in construction, easy to operate, and from which the chalk cannot easily escape.

20 Another object is to provide a chalking device wherein the chalk is compressed and forced into the fibres of the chalk line, as the line is drawn through the device.

Another object is to provide a device of 25 this character which can be easily and quickly taken apart for the purpose of replenishing the chalk.

A further object is to provide a device of this character which is so formed that, when 30 not in use, the line can be wound thereon, the device serving as a spool.

Other objects and advantages will be apparent from the following description when taken in connection with the accompanying 35 drawing.

In the drawing:

Figure 1 is an elevation of a line chalker made in accordance with the present invention.

40 Figure 2 is a vertical longitudinal central sectional view through the device, the compressing ball being in elevation.

Figure 3 is an enlarged sectional view through the compressing ball, showing the 45 recesses in the opposite sides of the ball.

Referring particularly to the accompanying drawing, 10 represents an open-ended cylindrical casing or shell, formed from any suitable material, and having its ends externally threaded for the reception of the end caps 11 and 12. The outer end portion of each cap is formed with a circumferential flange 13, for retaining the chalk line 14, when wound on the outer face of the casing. In the center of each of the caps there is formed an opening 15 within which

is secured an eyelet 16 for the chalk line, to prevent chafing thereof, as the line is pulled therethrough. Disposed within the casing, and having a central opening 17 therethrough for the line 14 to pass through, is a lead sphere 18, the opposite ends of the opening flaring, as shown at 19, to form recesses into which the line draws the powdered chalk, contained in the casing and surrounding the line and lead sphere, to cause the chalk to be compressed and packed into the fibres of the line. Disposed within the casing, and resting against one end of the body of powdered chalk, is a disk 20, the same having a central line receiving opening 21, within which is secured the eyelet 22. Secured to the inner face of the cap 12, at one end, and at its other end to the disk 20, is a coil spring 23, which serves to maintain the chalk in proper packed condition, and thereby prevents the same becoming loose and sifting through the openings mentioned. The portion of the outer end wall of each cap 11 and 12 which surrounds the eyelet is depressed inwardly toward the casing, as shown at 24. Secured to the outer face of the said end wall of each cap is a disk 25, having a recess 26 in the face which lies against the cap wall, and in the center of the disk is a small line receiving opening 27, surrounded by a recess 28. Disposed within each recess 28 is a rubber disk 29 having a central minute opening 29', through which the line is disposed, the portion of said rubber disk, opposite the recesses, being arranged to be flexed back and forth from one recess to the other, as the line is drawn through the casing and disk, from either direction. These rubber disks serve to prevent escape of the powdered chalk from the casing, because of the fact that the openings therein are slightly smaller than the diameter of the chalk line, and thereby fit snugly.

It will be seen that when the line is secured to a roof, or other place to be marked with a chalk line, the operator grasps the casing and moves the same toward the other end of the line, with the result that as the line runs through the casing the same will draw some of the powdered chalk into one of the recesses of the lead sphere, compressing the chalk into the line, any excess of chalk on the line being wiped therefrom by the walls of the small opening of the rubber disk 29. As the chalk is used, the spring

23 forces the disk 20 against the mass of chalk, thereby maintaining the chalk in a slightly compressed or compact condition and preventing any tendency of the chalk 5 to sift through the openings in the rubber disks, these latter being the only means of egress from the casing. It will also be noted that the casing may be drawn toward either end of the line, with equally effective chalk- 10 ing of the line.

The casing 10, in combination with the end caps 11 and 12, forms a spool onto which the line may be wound, when the device is to be placed in the pocket of the 15 workman, or in the tool box.

The parts, except for the lead sphere, are preferably formed from sheet metal, thereby providing that the device may be manufactured at a low cost.

20 As either cap 11 or 12 may be readily unscrewed from the casing, the replenishing of the chalk is rendered easy.

The disks 25 are secured to the caps 11 and 12 by means of the removable screws or 25 bolts, so that the rubber washers may be easily replaced when worn out.

What is claimed is:

1. A line chalking device including a container for powdered chalk having its ends 30 formed to receive a line therethrough, and means disposed wholly in the chalk in the container and carried by and movable with the line, and through which the line is arranged to slide, for packing and forcing chalk into the fibres of the line as the line is drawn therethrough.

2. A line chalker including a chalk container having its ends formed to receive a line therethrough, and means disposed wholly within the chalk in the container, and having a flared opening through which the line passes for compressing and forcing the chalk into the fibres of the line as the line is drawn therethrough.

3. A line chalker including a casing having centrally apertured ends through which a line is slidably disposed, the casing being arranged to contain powdered chalk, flexible wiping elements in the ends of the casing through which the line is slidable, and a centrally apertured element within the mass of chalk and through which the line passes, the walls of the aperture being formed for compressing the chalk into the fibres of the line as the line is drawn therethrough.

4. A line chalker comprising a casing, caps removably engaged on the ends of the casing and having central apertures through which a line is disposed, means within the casing for maintaining the chalk in a compact state, and a centrally apertured block within the chalk and receiving the line therethrough, the opposite ends of said central aperture being flared outwardly to receive chalk to be compressed into the line as the line passes therethrough.

5. A line chalker comprising a casing having its ends threaded, flanged and centrally apertured caps engaged on the ends of the casing, recessed disks carried by the caps, said disks being centrally apertured with a depression surrounding each aperture, the said caps each having a depression surrounding its central aperture, a spring pressed follower in the casing for pressing engagement with the contained chalk, and a sphere within the chalk having a central opening receiving the line therethrough the ends of the opening being flared outwardly to form recesses into which chalk is drawn by the line and compressed into the line as the line passes through the central opening.

In testimony whereof, I affix my signature, in the presence of two witnesses.

STANLEY F. NASH.
